GB 2079799 3/1999

* cited by examiner

Primary Examiner — Sandra Morris(74) Attorney, Agent, or Firm — Julia A. Glazer; Carrie Morgan Benjamin; David M. Weirich(57) CLAIM

The ornamental design for an oral care package, as shown and described.

DESCRIPTION

FIG. 1 is a perspective view of an oral care package;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken lines shown in the drawings are for illustrative purposes only and form no part of the claimed design.
